UNITED STATES PATENT OFFICE.

BEVERLY G. MOSS, OF WASHINGTON, NORTH CAROLINA.

LUMBER-MEASURER.

SPECIFICATION forming part of Letters Patent No. 666,904, dated January 29, 1901.

Application filed August 9, 1900. Serial No. 26,420. (No model.)

To all whom it may concern:

Be it known that I, BEVERLY G. MOSS, a citizen of the United States, residing at Washington, in the county of Beaufort and State 5 of North Carolina, have invented certain new and useful Improvements in Lumber-Measurers; and I do hereby declare the following to be a full, clear, and exact description of the invention, such as will enable others skilled 10 in the art to which it appertains to make and use the same.

My invention relates to improvements in lumber-measurers; and it consists in the novel features hereinafter described, reference being had to the accompanying drawings, which illustrate one form in which I have contemplated embodying my invention, and said invention is fully disclosed in the following description and claims.

20 The objects of my invention are, first, to provide a device for measuring large quantities of lumber, either in linear or square feet, the width and thickness being known; secondly, to provide means in connection with the said 25 device whereby the index-plates may be set back to zero, and, thirdly, to supply suitable means for supporting said device so that all thicknesses of lumber may pass thereunder without any further adjustment.

30 Referring to the drawings, Figure 1 represents a longitudinal section of a woodworking-machine, taken along the length of the bed. Fig. 2 is a section on line 2 2, Fig. 1. Fig. 3 is a section on line 3 3, Fig. 2; and Fig. 4 represents enlarged views of the index-plates, showing the graduation thereon.

40 A represents a woodworking-machine, of which B B are the revolving cutters, C C and D D the feed-rollers, E a strip of lumber, and F my improved lumber-measurer, b being the star-wheel thereof.

The casing F' of my device is provided with two lugs F² and F³, one at either end thereof, to which the mounting-spring G is secured.

45 An opening in the lower part of this mounting-spring permits a bolt G' to pass therethrough and engage the screw-threaded aperture in the guide-plate H, which is secured to the bed I of the woodworking-machine. This 50 construction, it will be seen, serves as an adjustable support for the device, and thus will allow all thicknesses of lumber to pass under

the measurer. Suitable openings x, y, and z are provided in the front of said casing for the display of graduated index-plates, herein- 55 after described.

Projecting through a suitable bearing in one end of the casing F' is an operating-shaft a, on the outer end of which is fixed the star-wheel b. On the other end of this shaft is a 60 worm a', gearing with a worm-wheel c, mounted on a shaft c², supported in a suitable bearing at one end and telescoping into a loose sleeve d at the other. A pin c' is rigidly secured in the shaft c² and enters the longitudinal slot d' in the sleeve d. The outer end of the sleeve above referred to extends out beyond the side of the casing and is provided with a knob K. The inner end of this sleeve has an operating spur gear-wheel d² fixed 65 thereon and is kept in engagement with the index-plate gearing, hereinafter described, by means of a spiral spring c³, which surrounds the shaft c² and bears against the worm-wheel c and the said operating gear-wheel d². It is 70 very plain that the slot c' will permit the operating mechanism to be thrown out and will thus allow the device to be set back to zero.

The index-plate gearing consists of the large gear-wheels e g i and the small pinions 80 f h, mounted on the shafts e' g', which carry the first two gear-wheels e g. These gear-wheels are arranged to mesh with the small pinion on the shaft of the preceding gear-wheel, the first gear-wheel e meshing with 85 the operating gear-wheel d². The ratio of these gear-wheels to their pinions and operating mechanism is as ten to one. One of the shafts which carry the gear-wheels, the middle one g shown in the drawings, is provided 90 with a thumb-piece for revolving the said shaft and setting back the index-plates when the operating mechanism is thrown out, which has been hereinbefore described.

The index-plates M N O, before referred to, 95 are secured to the front of the gear-wheels e, g, and i. Three of these gear-wheels and index-plates are shown in the drawings, but the number may be increased without departing from the spirit of my invention. Upon 100 the face of each of these index-plates are concentric circles, which are divided into ten equal parts by radial lines, the points of intersection of these radial lines and the first

circle from the edge representing the number of linear feet in certain lengths of boards, the second representing the number of square feet of lumber in the boards of a certain width, and the other circles representing the number of square feet in boards of still other widths.

What I claim, and desire to secure by Letters Patent, is—

- 10 1. The combination with a woodworking-machine provided with a table and feed mechanism, of a casing, openings in the front of said casing, index-plates carried by suitable gear-wheels within said casing, means for operating said index-plates, means for setting back said index-plates, a supporting-spring connected to both ends of said casing and means for securing said spring to said table, substantially as described.
- 15 2. The combination with a woodworking-machine provided with a table and feed mechanism, of a casing, openings in the front of said casing, index-plates carried by suitable gear-wheels within said casing, a thumb-piece mounted on the produced end of the shaft of one of said gear-wheels, a star-wheel in the path of the moving lumber, a worm on

the shaft of said star-wheel, a worm-wheel gearing with said worm, a loose sleeve fitting over the shaft of said worm-wheel, means for limiting the movement of said sleeve, a gear-wheel mounted on said sleeve adapted to normally engage the index-plate gearing, a supporting-spring connected to either end of said casing and means for securing said spring to said table, substantially as described.

3. The combination with a woodworking-machine provided with a table, of a casing, openings in the front of said casing, index-plates mounted on suitable gears within said casing, independent means of revolving said gears, an operating spur-gear mounted on a sliding sleeve, means for limiting the movement of said sleeve, means for normally retaining said operating spur-gear in engagement with said index-plate gearing, and means for operating said operating spur-gear, substantially as described.

In testimony whereof I affix my signature in the presence of two witnesses.

BEVERLY G. MOSS.

Witnesses:

FRANK C. KUGHER,
HENRY P. BRIDGMAN.
